ATTORNEY

UNITED STATES PATENT OFFICE

OTTO SPIESS, OF SAUGERTIES, NEW YORK

AWNING CONSTRUCTION

Application filed September 16, 1929. Serial No. 392,816.

My invention relates to awnings. In particular, the invention contemplates an arrangement and construction of the actuating mechanism whereby the awnings may be manipulated from the interior of the room over the window of which the awning is placed.

It has been the more common practice in constructing and erecting awnings to place the controlling mechanism on the outside of the building. In such constructions, it is necessary, in order to raise or lower the awning, for the operator to subject himself to the prevailing weather conditions existing outside the building either by opening the window, if the awning is placed over the window of an office or dwelling, or by going outside, if the awning is placed over a store window. In the case of dwellings and offices, it is particularly objectionable to necessitate opening the window in order to raise or lower the awning as it prevents the use of fixed screens and lessens the protection provided by removable screens, as the screens as well as the window must be opened. In some instances, attempts have been made to remedy this condition but the devices suggested were impractical either from the viewpoint of expense of installation or mode of operation.

In accordance with my invention, I provide a construction and arrangement of the actuating mechanism, such that an awning may be raised and lowered from the interior of the room over the window of which the awning is placed, that is inexpensive and simple in construction and operation relative to similar constructions. I employ a construction in which a tube having rounded edges for guiding the awning ropes into and out of the tube is entered through the casement of the window.

How I accomplish my object will be manifest from the following particular description of the embodiments of my invention taken in connection with the accompanying drawing in which:

Fig. 1 is an elevation of a window having an awning thereover, the awning being broken away to show the actuating mechanism; 50 and

Fig. 2 is a section taken on the line 2—2 of Figure 1 showing the awning in perspective and a modified form of actuating mechanism.

In the illustrated embodiments of my invention, there is shown a window casement 1 over which an awning 2 is placed. The awning 2, which is secured to the upper cross member 3 of the window casement in the usual manner extends over an awning frame 4. The frame 4 of the awning is U-shape, the ends of the U being pivotally secured to brackets 5 which are secured to the window casement slightly above the transverse center thereof. Awning ropes 6 and 7, which are secured to the cross bar 8 of the awning frame, extend over pulleys 9 and 10 secured to the window cross member 3, as shown in Fig. 2 or through a screw eye 11 as shown in Fig. 1 and through a tube 12 passing through the casement of the window.

The tube 11, through which the awning ropes are carried into the room, and which is preferably located at the upper corner of the window frame comprises two telescopic parts so that each part may be entered through an opening in the casement slightly larger than the exterior of the tube. The telescopic feature of the tube also permits adjustment of the tube for casements of various dimensions. The protruding ends of each section of the tube 12 are provided with rounded flanges as shown which act similar to a pulley in guiding the awning ropes into and out of the tube, the ropes sliding over the smooth curved surfaces.

For the purpose of securing the awning ropes, an ordinary rope winch 13 may be secured to the window casement.

It is obvious that various changes may be made in the illustrated embodiment of my invention above particularly described within the principle and scope of my invention as expressed in the appended claims.

Claims:

1. In an awning operating mechanism an awning frame adapted to be mounted on a window frame, two awning ropes one attached to each end of the frame, guides for the awning ropes adapted to be secured to the outer surface of the window frame, and a guide

tube for the awning ropes adapted to pass through the window frame near an upper corner and composed of two telescopic sections each of which has its outer end expanded and rounded off.

5 2. In an awning operating mechanism an awning frame adapted to be mounted on a window frame, two awning ropes one attached to each end of the frame, guides for 10 the awning ropes adapted to be secured to the outer surface of the window frame, and a guide tube for the awning ropes adapted to pass through the window frame near an upper corner and composed of two telescopic 15 sections each of which has its outer end expanded and rounded off, and the inner end of the section of lesser diameter having an internal bevel.

20 3. In an awning operating mechanism a guide tube for the awning ropes adapted to pass through the window frame near an upper corner comprising two telescopic sections each of which has its outer end expanded and rounded off, and the inner end of the section 25 of lesser diameter having an internal bevel.

In witness whereof, I hereunto subscribe my signature.

OTTO SPIESS.
